O,O-DIMETHYL S-(1-SUCCINIMIDOETHYL) PHOSPHORODITHIOATE AND INSECTICIDAL COMPOSITIONS CONTAINING THE SAME

Albert H. Haubein, Newark, Del., assignor to Hercules Incorporated, a corporation of Delaware
No Drawing. Filed Jan. 11, 1965, Ser. No. 424,843
6 Claims. (Cl. 167—33)

This invention relates to insecticides and more particularly to organophosphorus compounds having long residual activity.

It is known that phosphorodithioates of many kinds have insecticidal activity. It is also known in German Patent 930,446 that O,O-dimethyl S-(1-succinimidoethyl) phosphorodithioate is toxic to some insects and in U.S. 2,902,493 that O,O-diethyl S-(2-succinimidoethyl) phosphorodithioate is also toxic to insects. These insecticides are biodegradable insecticides and are thus non-persistent, but they do not have very long residual activity. Biodegradable insecticides are necessary on food crops since the insecticidal activity must be absent by the time of harvest. Biodegradable insecticides are desirable from the standpoint of avoiding possible contamination of rivers and streams. While biodegradability is desirable from the standpoint of safety, a residual activity lasting for prolonged periods is particularly desirable in those cases where the insects are controlled by contact with surfaces which have been treated.

In accordance with the present invention, it has now been found that O,O-dimethyl S-(1-succinimidoethyl) phosphorodithioate is a biodegradable insecticide having a long residual toxicity.

The long residual toxicity of this compound is readily demonstrated by applying O,O-dimethyl S-(1-succinimidoethyl) phosphorodithioate at the rate of 25 mg. per square foot of surface to the inner surface of a non-porous unwaxed paper drinking cup and leaving the cup exposed to ambient conditions of about 78° C. and 50% relative humidity for a period of time up to two months and determining the kill of adult mosquitoes placed therein for one-hour periods from the time to time.

In this residual toxicity test procedure, a 0.25% aqueous emulsion of O,O-dimethyl S-(1-succinimidoethyl) phosphorodithioate was pipetted into a non-porous, unwaxed paper cup in an amount sufficient to cover the surface with 25 mg. per square foot and this emulsion was spread all over the inner surface until dry. Then the cups were allowed to stand open for 2 days at 78° C. and 50% relative humidity. Ten female, unfed, adult mosquitoes, anesthetized with CO₂, were placed on an 18-mesh stainless steel wire screen and covered by a treated cup, the screen being open to the air. The mosquitoes revived in a few minutes and walked on the walls of the cup for an hour. They were again anesthetized with CO₂ and were placed in a 5-inch circular cage of 14-mesh stainless steel for 24 hours. The percent dead in 24 hours was then determined. A second group of mosquitoes was placed in the cup 7 days later and the toxicity determined again. This was continued until an appreciable drop in toxicity was noted. The following data, showing the improvement in the present invention, were obtained on O,O-dimethyl S-(1-succinimidoethyl) phosphorodithioate (Compound A) of this invention and on O,O-diethyl S-(2-succinimidoethyl) phosphorodithioate (Compound B) and O,O-dimethyl S-(1-succinimido-

2

methyl) phosphorodithioate (Compound C) of the prior art:

5	Compound	Concen- tration, mg./it. ²	Days of Residual Toxicity (Percent Kill)				
			2	9	16	42	63
10	A	{ 25 50	100 100	100 100	{ 100 100	100	60
B	{ 25 50	10 70	0 0	{ 0 0	0	0	0
C	{ 25 50	10 50	0 30	{ 0 30	0	0	0

Similar residual toxicity is shown against other insects such as plum curculio on the skin of apples and against 2-spotted mites on lima bean seedlings. Compounds A, B and C are biodegradable when absorbed by the plant, as well as when in contact with unsterilized soil.

The following example, in which parts and percentages are by weight, is given to illustrate the invention.

Example 1

To 38 parts of N-vinyl succinimide in 40 parts of benzene was added 53.7 parts dimethyl dithiophosphoric acid in about 100 parts of benzene dropwise over a 0.5 hour period. The resulting solution was heated at 80° C. under reflux for 6 hours, cooled and washed at 35° C. with water and 5% aqueous sodium bicarbonate solution. On cooling below room temperature, 39.3 parts crystalline product separated. After distilling off the benzene and adding a little ether, an additional crop of 30.5 parts crystalline product was obtained. The product, on crystallization from a mixture of benzene and petroleum ether, was O,O-dimethyl S-(1-succinimidoethyl) phosphorodithioate of M.P. 95—97° C. Analysis: P, 11.1%; S, 23.2%; C, 34.19%; H, 5.36%.

The reaction between the N-vinyl succinimide and O,O-dimethyl dithiophosphoric acid takes place at a temperature within the range of 25—120° C. The reaction between N- α -chloroethyl succinimide and O,O-dimethyl dithiophosphoric acid, or a salt thereof such as the ammonium salt, also yields the product of this invention. Solvents for the latter reaction include acetone and acetonitrile in addition to benzene or toluene.

The O,O-dimethyl S-(1-succinimidoethyl) phosphorodithioate of this invention is useful as a toxicant in insecticide compositions for many types of insects and is used preferably as a dust or as an aqueous emulsion.

Dusts are formulated from a dust concentrate or from a liquid concentrate. It is common practice for a formulator to dilute a dust concentrate with a clay or similar powdered solid to the desired dilution for application. The dust concentrate, when compounded with a wetting agent, is a wettable powder, which is emulsifiable in the field.

Aqueous emulsions are formulated by a formulator from a liquid concentrate. The formulator will use either a liquid concentrate containing the toxicant and a surface-active dispersing agent, or a liquid concentrate, water, and a surface-active agent. A liquid concentrate containing a surface-active agent will be used by the man in the field who wishes to prepare aqueous emulsions economically.

The concentrate is preferably a composition of the toxicant of this invention and a non-volatile adjuvant which is solid, as in the case of dusts, or is liquid, as in the case

here an aqueous emulsion is produced or in the case here a formulator mixes the liquid concentrate with dust to form a more dilute dust. A concentrate of toxicant and a volatile adjuvant such as a volatile organic solvent will be useful also for combination with a surface-active adjuvant by a formulator of concentrates.

The concentration of the toxicant in a concentrate will be 10-90% in the case where a volatile organic solvent is used, and 25-90% where there is no volatile organic solvent.

The solid adjuvant of the composition is selected according to the properties desired from such solids as clays, fuller's earth, diatomaceous earth, rosin, petroleum hydrocarbon insoluble pine wood resins, and surface-active dispersing agents. The solid adjuvant will thus in many cases have surface-active, spreading or sticking properties and, in some cases, will be used with water or organic solvent to aid in the mixing process.

The liquid adjuvant of the composition is selected from the non-volatile liquids such as petroleum oils, paraffin, oils, lubricating oils and rosin oils, and volatile liquids such as toluene, benzene, xylenes, volatile petroleum fractions, acetone, methyl ethyl ketone, and diacetone alcohol.

The concentrate containing a surface-active agent will contain usually 0.01 to 2 times as much surface-active agent as toxicant and other components to be dispersed in formation of an aqueous emulsion, and preferably 0.05 to 0.5 times as much surface-active agent as material to be dispersed. The concentrate which is a solution of all components such as a concentrate of toxicant and surface-active agent which is soluble in organic solvents preferably also contains a volatile organic solvent in an amount in the range of 0.1 to 10 times the weight of toxicant when necessary to improve fluidity.

The concentrate of toxicant and liquid non-volatile adjuvant generally contains 5-25% surface-active agent to aid in emulsification. A concentrate containing a surface-active agent is, by well known technique, formed into water-in-oil or oil-in-water emulsions. For the former, 10-25% surface-active agent is used and, for the latter, 15-20% is used. A concentrate containing toxicant, non-volatile adjuvant, and surface-active agent is emulsified in the field without further diluting but it is, at times, advantageous to dilute this concentrate with oil containing a surface-active agent when it is desired to obtain dilute water-in-oil, i.e., invert, emulsions. The surface-active agents which are used are any of those anionic, cationic or non-ionic surface-active agents well known in the art. See Chemistry of Insecticides, Fungicides and Herbicides (Donald E. H. Frear, 2nd ed. 1948, pages 280-7). The surface-active agents which are particularly suitable are the polyoxyethylene compounds such as reaction products of alcohols or amines with ethylene oxide. Other surface-active agents and methods of using them for various types of emulsions are to be found in Surface Active Agents—Their Chemistry and Technology, Anthony M. Schwartz and James W. Perry, Interscience Publishers Inc., New York, 1949,

and in Emulsions: Theory and Practice, Paul Becher, Reinhold, 1957.

5 A concentrate of equal parts each of acetone, O,O-dimethyl S-(1-succinimidoethyl) phosphorodithioate and Tween 20 (sorbitol monolaurate polyoxyethylene derivative) was prepared and added to distilled water, with rapid stirring, to form emulsions of various concentrations from 0.05% to 0.0005% toxicant. A 0.025% emulsion gave 100% kill of houseflies. An 0.0025% emulsion gave a 100% kill of Mexican bean beetle. A 0.005% emulsion gave a 100% kill of pea aphids. A 0.0005% emulsion gave a 100% kill of two-spotted mites. The residual activity, as indicated above, shows the superiority of the toxicant of this invention when applied to the habitats of mosquitoes. The toxicant of this invention, while high in residual activity on the habitats of many insects, is nevertheless not in the persistent class since it is biodegradable, for example, in soil.

10 The O,O-dimethyl S-(1-succinimidoethyl) phosphorodithioate of this invention can be used in combination with other insecticides where desired. The other insecticide need not be biodegradable since the biodegradability of the present insecticide will act as an improver of the properties of the combination.

15 25 What I claim and desire to protect by Letters Patent is:

1. As an insecticidally active compound having a high residual activity O,O-dimethyl S-(1-succinimidoethyl) phosphorodithioate.

20 30 2. An insecticide concentrate comprising O,O-dimethyl S-(1-succinimidoethyl) phosphorodithioate as a toxicant and a non-volatile dispersing adjuvant therefor.

3. An insecticide concentrate comprising O,O-dimethyl S-(1-succinimidoethyl) phosphorodithioate as a toxicant and a solid non-volatile dispersing adjuvant therefor.

35 35 4. An insecticide concentrate comprising O,O-dimethyl S-(1-succinimidoethyl) phosphorodithioate as a toxicant and a surface-active dispersing agent in an amount effective for dispersing the toxicant in water.

40 40 5. An insecticide concentrate comprising O,O-dimethyl S-(1-succinimidoethyl) phosphorodithioate as a toxicant, an organic solvent for the toxicant and a surface-active dispersing agent soluble in said solvent in an amount effective for dispersing the toxicant in water.

45 45 6. An aqueous emulsion comprising a major amount of water and a minor but insecticidally effective amount of O,O-dimethyl S-(1-succinimidoethyl) phosphorodithioate and a surface-active dispersing agent.
